DEVICE FOR ROUNDING THE CORNERS OF
VARIOUS TYPES OF PAPER OR CARD STOCK
James E. Rogers, 4777 Amesbury Way, Columbus, Ohio
Filed Sept. 13, 1963, Ser. No. 308,770
4 Claims. (Cl. 90—15)

My invention relates to a device for rounding the corners of various types of paper or card stock. It is particularly useful for rounding the corners of sheets of paper, cards or similar paper items disposed in a pack or group in face-to-face contact but is capable of rounding the corners of other items arranged in packs, stacks, or groups.

The present invention provides for the purpose indicated an extremely simple machine or device which can be manufactured at low cost and which can be operated with a minimum of skilled labor.

My device provides a holder for the stock and a cutter associated therewith which will successively engage the sheets or cards as they and the cutter are moved relatively into association. The cutter revolves in a plane perpendicular to the face of the oncoming sheets of stock about an axis extending in the direction of the plane of the sheets. The plane of revolution of the cutter intersects the angle of the adjacent edges of the sheets of stock. The cutter is provided with a cutting edge having a radius or curve transversely of its plane of movement. Contact of the cutter with each successive sheet will round the corner thereof.

In the accompanying drawings, I have illustrated the preferred form of machine embodying my invention but it is to be understood that variations may be made without departing from the basic principle of my invention.

In the drawing:

FIGURE 1 is an isometric view of a machine embodying my invention.

FIGURE 2 is a vertical, transverse, sectional view taken along line 2—2 of FIGURE 1.

FIGURE 3 is an enlarged, schematic, transverse sectional view illustrating how the cutter removes the corner of a sheet of stock.

FIGURE 4 is a vertical, longitudinal, sectional view taken along line 4—4 of FIGURE 2.

With reference to the drawing, the device may be carried by a suitable table 10 which has an electric driving motor 11 mounted therebeneath. Above the table, there is provided a stock holder 12. This holder is provided with the side walls or guide portions 13 which are arranged, at an angle, usually at a right angle, relative to each other, corresponding to the angular relationship of the adjacent edges of the sheets of stock. The holder is supported on the table 10 with its guide walls 13 at an angle relative thereto, in this instance, being at 45° relative to the upper surface of the table. Thus, there is provided a V-shaped holder or guide for receiving a pack, stack or group of sheets which constitutes the stock.

At the vertex of the V-shaped holder, at a suitable position along the length thereof, a slot 14 is provided. This slot extends outwardly and upwardly into a portion of each of the walls 13. A corresponding slot 15 is provided in the table 10 directly below the slot 14. A cutter member 16 has a cutting edge projecting upwardly through the slot 15 into the slot 14 and upwardly slightly beyond the vertex, which is indicated at V in FIGURE 3, where the inner guide surfaces of the walls 13 would meet if continued and if the slot 14 were not provided.

2

In the example shown, I have illustrated the cutter 16 as being in the form of a circular saw blade which rotates about the axis 17 of the drive shaft of the motor 11. This blade is of disc-like form with peripherally projecting teeth. The teeth of this saw blade are ground with a transverse radius 18 corresponding to the curve to be imparted to each sheet of stock at its corner. However, this is merely a convenient form of cutter and it is to be understood that other cutters may be substituted since the cutter merely needs to provide a cutting edge revolving about an axis extending in the direction of the planes of the sheets of stock, at a right angle to the slot 14, and revolving in a plane perpendicular to the faces of the sheets. This plane must intersect the angle of the guide walls or portions 13 of the holder 12, such portions being at a relative angle corresponding to the angle of the adjacent edges of the sheets. If such edges are at right angles, the guide portions 13 will be correspondingly at a right angle and the plane of rotation of the cutter will bisect the angle.

In using this device, it is merely necessary to position the stock in the holder at the vertex thereof. Then the stock is moved along into association with the cutter 16 so that each sheet is successively engaged by the cutter 16 at its corner. However, if desired, the cutter 16 may traverse the holder 12 in an elongated slot corresponding to the slot 14. The axis of rotation 17 of the cutter 16 extends in a direction at a right angle relative to the direction of movement of the stock into association with the cutter. This position will remove the portion of the corner of each sheet indicated by the dotted lines in FIGURE 3, this removed portion being the portion which extends down into the slot 14.

It will be apparent that this invention provides a simple, inexpensive device for performing a difficult operation in a simple manner.

According to the provisions of the patent statutes, the principles of this invention have been explained and have been illustrated and described in what is now considered to represent the best embodiment. However, it is to be understood that, within the scope of the appended claims, the invention may be practiced otherwise than as specifically illustrated and described.

Having thus described my invention, what I claim is:

1. A device for rounding the corners of sheets of stock disposed in face-to-face contact comprising a holder for receiving and holding the stock, said holder having guide portions at an angle corresponding to the angle of the adjacent edges of the sheets of stock at the corner to be rounded for receiving said stock, a cutting member at the angle between the guide portions and extending into the holder within the angularly related guide portions, said cutter being movable in a plane intersecting the angle at its vertex and having a cutting edge which is curved transversely of said plane, said plane being perpendicular to the plane of the sheets of stock, and means for traversing the holder and cutter relatively.

2. A device according to claim 1 in which the stock has its adjacent edges at right angles and the guide portions of the holder are at right angles, said plane of the cutter bisecting the angle between the guide portions.

3. A device according to claim 1 in which the cutting edge revolves about an axis disposed transversely of the holder in a plane at a right angle to said slot.

4. A device according to claim 3 in which the cutter is in the form of a disc-like saw blade with peripheral teeth, the teeth being curved transversely.
